US00D931298S

(12) **United States Design Patent** (10) Patent No.: **US D931,298 S**
Hagele et al. (45) Date of Patent: **** Sep. 21, 2021**

(54) **DISPLAY SCREEN OR PORTION THEREOF WITH GRAPHICAL USER INTERFACE**

(71) Applicant: **Apple Inc.**, Cupertino, CA (US)

(72) Inventors: **Markus Hagele**, San Francisco, CA (US); **Stephen O. Lemay**, Palo Alto, CA (US); **Wyatt R. Mitchell**, San Francisco, CA (US); **Parthiban Mohanraj**, Cupertino, CA (US)

(73) Assignee: **Apple Inc.**, Cupertino, CA (US)

(**) Term: **15 Years**

(21) Appl. No.: **29/693,072**

(22) Filed: **May 30, 2019**

(51) LOC (13) Cl. **14-04**

(52) U.S. Cl. **USPC D14/485**

(57) **CLAIM**

The ornamental design for a display screen or portion thereof with graphical user interface, as shown and described.

DESCRIPTION

The sole FIGURE is a front view of a display screen or portion thereof with graphical user interface showing the claimed design.

The peripheral dashed broken lines illustrate a display screen or portion thereof, and form no part of the claimed design. The interior broken lines illustrate portions of the graphical user interface which form no part of the claimed design. In the sole FIGURE, within the interior rectangular broken lines, the half-tone portions form no part of the claimed design.
